Des. 238,247
Patented Dec. 30, 1975

238,247

RETRACTABLE KNIFE

John F. Thomas III, Wyckoff, N.J., assignor to CBS Inc., New York, N.Y.

Filed Dec. 23, 1974, Ser. No. 535,314

Term of patent 14 years

Int. Cl. D8—03

U.S. Cl. D8—99

FIG. 2

FIG. 1

FIG. 3

FIG. 4

FIG. 5

FIG. 6

FIG. 1 is a perspective view of a retractable knife showing my new design;

FIG. 2 is a top plan view thereof;

FIG. 3 is a bottom plan view thereof;

FIG. 4 is a side elevation view of the side thereof opposite to the side shown in FIG. 1;

FIG. 5 is an end view thereof, as viewed from the left in FIG. 4; and

FIG. 6 is an end view thereof, as viewed from the right in FIG. 4.

I claim:

The ornamental design for a retractable knife, substantially as shown and described.
